FINGER PENHOLDER

Filed May 24, 1928

INVENTOR.

Francis H. Macdonald
BY *John A. McGehee*
ATTORNEY

UNITED STATES PATENT OFFICE

FRANCIS H. MACDONALD, OF EDGEMERE, NEW YORK

FINGER PENHOLDER

Application filed May 24, 1928. Serial No. 280,137.

This invention relates generally to writing implements, and has more particular reference to a novel index finger holder for writing.

- 5 The invention has for an object the provision of a device of the class described, which is of simple durable construction, desirable and efficient in action, and which can be manufactured and sold at a reasonable cost.
- 10 The invention proposes the use of a resilient finger member preferably made of celluloid or other hard and elastic material and adapted for engagement upon the index finger, or if desired upon another finger, of a person, and arranged for supporting a pen nib for writing. Preferably the pen nib should be in line with the longitudinal center of the finger member which should be tapered from the front towards the rear for engaging the person's finger, and also arranged for gently clamping the finger for self holding purposes. A means for extending the nib at various positions from the finger member may be provided, and also a means for tilting the nib at 25 various angles relative to the finger member.

An important feature of the device is that it may be easily carried in one's pocket when not in use, and when in use conveniently and comfortably engages the user's finger. Since 30 the device naturally engages the wearer's finger it is not necessary to hold same and cause needless tiring. In addition no convexed surface is presented against the finger or fingers which acts to press-in and stop circulation within the fingers as is common with present day pens.

For further comprehension of the invention, and of the objects and advantages thereof, reference will be had to the following description and accompanying drawings, and to the appended claim in which the various novel features of the invention are more particularly set forth.

In the accompanying drawing, forming a 45 material part of this disclosure:

Fig. 1 is a perspective view showing the device applied on one's hand.

Fig. 2 is a perspective view of the device, per se.

50 Fig. 3 is a plan view thereof.

Fig. 4 is an end view, looking in the direction of the line 4—4 of Fig. 2.

Fig. 5 is a fragmentary vertical sectional view, taken on the line 5—5 of Fig. 3.

The reference numeral 15 indicates generally a person's hand with the device 16 applied on the index finger 17 thereof, and thumb 18 is shown resting against the device for steadyng purposes as during writing.

The device 16 comprises a finger engaging member 19 of circular form in transverse cross section and tapering from the front to the rear in frusto-conical fashion and having overlapping sides disposed at the bottom thereof, and made preferably of celluloid or other hard and elastic material for adaption to slightly clamp upon the index finger.

The finger member 19 has a flat top 27 on which the base 20', the cover 21' and a nib support member 22 for holding the nib 23 are pivotally mounted, by a pin 28. The flat top 27 is formed with a plurality of apertures 29 on the arc of a circle scribed from 28 as a center, and pins 30 engage thru the ends of the cover 21' and base 20' and into certain of the apertures 29 for holding the nib 23 at desired angular positions relative to the longitudinal length of the member 19. This feature is of advantage in cases where the user prefers an angularly tilted pen.

It is to be understood that my holder may be used not only for a pen but also for holding a pencil or any other writing implement which may be attached to one's finger for the purpose of writing or drawing.

While I have shown and described the preferred embodiment of my invention, it is to be understood that I do not limit myself to the precise construction herein disclosed and the right is reserved to all changes and modifications coming within the scope of the invention as defined in the appended claim.

Having thus described my invention what I claim as new and desire to secure by United States Letters Patent is:

In a finger pen holder, a finger member arranged for engaging one's finger, and having a flat top, a base pivotally mounted on the said flat top, means for holding a pen nib, secured on the base, the said flat top being

5 formed with a plurality of apertures on the arc of a circle scribed from the base pivotal point, and pins engaged thru the base and into certain of the apertures for holding the base at fixed angular positions for holding the pen nib at angular positions relative to the length of the finger member.

In testimony whereof I have affixed my signature.

10 FRANCIS H. MACDONALD.
